UNITED STATES PATENT OFFICE.

THOMAS ERNEST HALLIDAY, OF BISHOPSTOKE, ENGLAND.

HEAVY-OIL-CARBURETTING SYSTEM FOR INTERNAL-COMBUSTION ENGINES.

1,137,057.

Specification of Letters Patent.

Patented Apr. 27, 1915.

Application filed January 30, 1912. Serial No. 674,396.

To all whom it may concern:

Be it known that I, THOMAS ERNEST HALLIDAY, a subject of the King of England, and resident of "Glenesk," Bishopstoke, Hampshire, England, have invented a Heavy-Oil Carbureting System for Internal-Combustion Engines, of which the following is a specification.

This invention relates to a carbureter and system for enabling paraffin and similar heavy oils to be efficiently carbureted.

Usually carbureters for use with heavy oils are so arranged that the oil-gas and air are heated considerably so as to convert the liquid into a vapor, and this hot gas is sometimes moistened, and the complete mixture is then admitted to the engine. The moistening is effected either in the carbureter itself, or some water or steam is admitted to the engine cylinder.

The system which forms the subject of the present invention differs considerably from what has previously been proposed inasmuch as the liquid is first mixed with air by means of a spray carbureter of some suitable type and this mixture is then passed through a heater so that it becomes vaporized, after which, just before admission to the engine, this vaporized mixture is moistened by the addition of a water spray. By separating the three processes, mixing, vaporizing and moistening, in this manner, and effecting them in the sequence mentioned, I have found that very good results are obtained which cannot be effected by methods hitherto proposed.

I am quite aware that the broad idea of carbureting, vaporizing, and then moistening, is not in itself novel, but in previous cases the three processes have been caused to overlap or have been effected in the same apparatus. In my case the three processes are completely separate and the carbureter is quite distinct from the vaporizer, while the moistening is effected as late as possible or convenient before the gas is admitted to the engine.

In the accompanying drawings: Figure 1 is a side elevation showing the application of the invention to a four cylinder engine in which all the valves are arranged on one side. Fig. 2 is a central vertical section through the main portion of the carbureter.

Like letters indicate like parts in both views.

In this construction there may be two

float chambers of some ordinary type (only one of these appears in Fig. 1,) supplying a jet nozzle A, a two-way valve or cock B being provided to enable the jet nozzle to be supplied either with petrol or heavy oil such as paraffin, the petrol, of course, being used for starting purposes only. Surrounding the jet nozzle is a choke tube C, and around this is a passage D in the wall of which are extra air intakes E controlled by a spring loaded sleeve valve F which opens in the usual manner to admit diluting air as required.

The valve F takes the form of a sleeve provided at F² with a hole adapted to register with the air inlet E when the valve moves over to the left. This movement is resisted by the spring illustrated which abuts up against a radial flange on the sleeve at the right hand end and a fixed abutment C² on the choke tube at the left hand end.

In the particular construction of engine illustrated there are only two gas inlets to the cylinders, these being shown at Y. The inlets Y communicate with chambers in the cylinder casting from which the adjacent inlet valves admit the gas to the cylinders. The exhaust valves are arranged at the extreme ends of each twin cylinder casting. There are consequently four exhaust outlets shown at Z.

The exhaust outlets Z communicate with exhaust pipes X and cast around this branch exhaust pipe X is a hollow chamber H with which the induction pipe G communicates. This chamber H also communicates with the gas inlets Y so that when suction is set up the cylinders draw their mixture along the pipe G through the chambers H cast around the exhaust pipes and therefrom to the inlet Y and so to the cylinders. The chambers H are of course raised to a high temperature by the exhaust gases passing down the pipes X and they therefore constitute vaporizers whereby the mixture provided by the carbureter is vaporized or gasified before admission to the cylinders.

At or close to the connections Y to the cylinders are arranged pipes J communicating with a moistening device, through which hot air is drawn. The moistening device may be of any suitable type. In the construction illustrated in Fig. 1 it comprises a nozzle K to which water is supplied, and a choke tube L similar to those employed for the fuel supply of carbureters. Thus the paraffin gas just before admission

to the engine is diluted with hot air led to the choke tube L by means of the pipe N and containing moisture in any required degree so that high compressions may be used without fear of preignition.

In the carbureting portion of the system it is desirable that complete mixing be effected and for this purpose the air is given a helical or rotary motion as far as possible. Thus the interior periphery of the passage D around the choke tube may be shaped to give the air a whirling motion, and the throttle disk O may be provided with helical vanes or the like, and if desired one or more sharp pitched screws or similarly shaped baffles may be arranged in the induction pipe for the same purpose.

For simplicity the choke tube and jet nozzle for the moistening device may be mounted on the carbureter and the moist air led therefrom to the inlets by suitable piping. This is the case in Fig. 2, the moistening device being arranged at P in a passage cast in the carbureter wall.

It has been found that with this system

very efficient and satisfactory results are obtainable in a simple manner.

Having now fully described my said invention what I claim and desire to secure by Letters Patent is:—

In a heavy oil carbureter system, means for mixing air with the fuel, means for receiving said mixture and vaporizing it at a point sufficiently remote from the mixing means whereby the temperature of the mixing means is not increased by the heat from said vaporizing means, and means apart from the mixing means and the vaporizing means for moistening the vaporized mixture, all of said means being separate and apart from each other and arranged to act upon the fuel charge in the order named.

In testimony whereof I have hereunto set my hand in the presence of two subscribing witnesses.

THOMAS ERNEST HALLIDAY.
